HAROLD D. ARNOLD, OF EAST ORANGE, NEW JERSEY, ASSIGNOR TO WESTERN ELECTRIC COMPANY, INCORPORATED, OF NEW YORK, N. Y., A CORPORATION OF NEW YORK.

MEANS AND METHOD FOR SECRET SIGNALING.

1,356,686.

Specification of Letters Patent. Patented Oct. 26, 1920.

Application filed December 30, 1916. Serial No. 139,945.

To all whom it may concern:

Be it known that I, HAROLD DE FOREST ARNOLD, a citizen of the United States, residing at East Orange, in the county of Essex and State of New Jersey, have invented certain new and useful Improvements in Means and Methods for Secret Signaling, of which the following is a full, clear, concise, and exact description.

10 This invention relates to means and methods for secret signaling by apparently steady light beams.

15 The object of this invention is to provide a simple and efficient means for signaling by light beams of such a character that the variations produced in the beams will be invisible to the naked eye, but can be readily detected by an observer provided with the necessary detecting apparatus as hereinafter 20 described.

25 For the accomplishment of this purpose, this invention makes use of the well-established fact that the human eye unaided is insensitive to many of the qualities or characteristics of light beams. The particular characteristic employed in the following application of this invention is the inability 30 of the eye to detect rapid oscillations of a high frequency. Thus, to the eye, the light 35 is apparently the same from a source, such as a mercury lamp, an ordinary electric light bulb or an arc or any other kind of a suitable lamp lighted by electricity, whether it is lighted by an alternating current of a high frequency or by a direct current, provided, however, that the effective lighting value is the same for the two currents.

40 For the better understanding of this invention, reference is made to the accompanying drawing, which illustrates this invention as adapted to a signaling system in which the signaling is accomplished by varying the frequency of the electrical current supply of a light source in accordance with 45 the signals to be transmitted, and in detecting said variations in a stroboscopic manner.

45 In the transmitting station illustrated in the drawing, 3 is a source of light, shown here as an electric lamp, which may be supplied with direct current from the source of current 4, or may be supplied with an alternating current from the generator 5. The lamp is preferably one in which the intensity 50 of the light is sensitive to rapid changes in

current, such as that supplied by the alternating generator. 7 is a means by which the light may be alternately lighted by direct current and by alternating current. At the receiving station 9 is a stroboscopic means, shown here as a rotating perforated disk, 60 which serves to detect the above mentioned changes in the current supply.

At the transmitting station the movable member 7 has an insulating block 10 which prevents a short circuit between the two adjustable contacts 13 and 14. With the contact 13 in the position illustrated, the resistance 17 is in series with the battery 4 and is of such a high value that practically no direct current flows through the lamp. But with the contact 14 in the position illustrated, the resistance 19 is not included in the path of the alternating current from generator 5, so that little or no resistance is offered to the path of the alternating current 75 through the lead wires 11 and 12 to the lamp 3, which path the current takes in preference to the high impedance path containing the battery 4. The frequency of this alternating current should be above that to which the 80 human eye is sensitive probably above thirty cycles per second.

At the receiving station the disk 9 is mounted on a shaft 21. On this shaft is a pulley 22, which is connected to a source of 85 power (not shown) by the belt 23 for rotating the disk at any desired speed. Near the outer edge of the disk, and spaced at regular intervals, are some rectangular slits or apertures, 24, through which the light from the 90 transmitting station may be observed. If the frequency with which one aperture follows another is exactly twice that of the frequency of the generator 5, the eye, while gazing through said apertures, will be able 95 to detect no change or flickering in the light received from the source 3 at the transmitting station as at every period the light is visible, the current through the source 3 will have the same value as the period before. 100 If, however, the speed of the disk is changed so that the apertures pass the line of sight at a frequency slightly greater or less than twice the frequency of the generator 5, a flickering will be observed, due to the fact 105 that the light is being viewed through each aperture with the current in the filament 18 in a different portion of its cycle. This flick-

ering is, therefore, an indication that the lamp is lighted by an alternating current.

If, now, the movable member 10 is adjusted so that the contacts 13 and 14 occupy the positions 13' and 14', respectively, resistance 19 is then included in the path of the alternating current from the generator, which resistance is of such a value that the alternating current will practically be suppressed. Resistance 17, however, will be removed from the direct current circuit so that the current from the battery 4 will have a path of little resistance through contact 13', lead wires 11 and 12 to the lamp. Thus, with the adjustable contacts in the positions 13' and 14', the lighting of the lamp is accomplished by the direct current only. With such a source of current the light will consequently be steady so that no flickering at the receiving station will be observed through the stroboscope.

Hence, if by moving the sliding key 7, the current supplied to the lamp is varied from an alternating current to a direct current in accordance with the signals to be transmitted, an observer, looking through the apertures of the disk rotating at the proper speed, will be able to detect said signals, since the light will flicker when the lamp is lighted by an alternating current, but will remain steady when the lighting is done by a direct current. The signals are not visible, however, unless some suitable means, as the rotating disk illustrated, is used to detect them.

It is preferable that the relation between the values of resistances 17 and 19 should be such that for all positions of the sliding key between the points 13 and 14 and the points 13' and 14' the effective sum of the alternating current and the direct current will be constant so that the effective intensity of the light should remain constant as the key is moved from one position to another. Such a condition prevents the casual observer from detecting the signals and also increases the ease of the detection of the signals at the receiving station. 25 is a large condenser inserted in the alternating current generator circuit to prevent the flow of the direct current through said generator; but the condenser offers little or no impedance to the passage of the alternating current. 26 is a large choke coil in the direct current circuit which offers little or no resistance to the direct current, but prevents the alternating current from passing through the side circuit containing the battery 4.

It is apparent that any suitable means may be employed other than the one illustrated for changing the effective lighting current from alternating to direct. It is also evident that any source of light deriving its energy from an electrical current, such as a mercury lamp or an electric arc, for

example, may be substituted for the lamp shown. Various other modifications of the system may be made without departing in any wise from the spirit of this invention.

What is claimed is:

1. In a secret signaling system, a single source of light, means for varying an invisible characteristic of the visible light waves from said source in accordance with the signals to be transmitted while transmitting a substantially constant quantity of said visible light waves, and means for detecting said variations. 70

2. The method of secret signaling which consists in invisibly varying the frequency 80 of a light beam in accordance with the signals to be transmitted and in detecting said signals stroboscopically.

3. The method of secret signaling which consists in alternately transmitting a steady 85 light and light of a given frequency in accordance with the signals to be transmitted while transmitting a substantially constant quantity of the normally visible characteristics of said light, and in rendering said signals visible. 90

4. In a secret signaling system, a source of light, two sources of current for said light source, one of which is an alternating current source, means for alternately lighting 95 said light source by the two said current sources in accordance with the signals to be transmitted, and means for detecting said signals.

5. In a secret signaling system, an electric 100 lamp and a source of current therefor, means for varying the current supplied to said lamp in accordance with the signals to be transmitted while transmitting a substantially constant quantity of the visible 105 characteristic of the light from said lamp, and means for detecting said variations.

6. In a secret signaling system, an electric lamp and a source of current therefor, means for varying the current supplied to 110 said lamp in accordance with the signals to be transmitted thereby changing the character of the light from said lamp, and a stroboscope whereby said changes may be detected. 115

7. In a secret signaling system, a source of light, means for causing said source to emit steady light, a second means for causing said source to emit intermittent light having a frequency above that to which the 120 naked eye is sensitive, means for alternately operating said source by said first means and by said second means in accordance with the signals to be transmitted and while transmitting a substantially constant quantity of the visible characteristics of the light from said source and means for detecting said signals.

8. In a secret signaling system, a source of light, a source of direct current for said 125

5 light, a source of alternating current for said light, means for alternately impressing said currents on said light source thereby varying invisibly its light emission in a predetermined order, and a receiver for detecting said variations.

9. In a secret signaling system, a source of light, means for causing said source to emit steady light, means for causing said 10 source to emit intermittent light having a frequency above that to which the naked eye is sensitive, means for alternately operating said source by said first means and by said second means in accordance with the signals 15 to be transmitted, and a receiver for detecting said signals, said receiver consisting of a means for intermittently allowing said light to fall upon the observer's eye.

10. In a secret signaling system, an electric 20 lamp, a source of direct current for said lamp, a source of alternating current for said lamp, means for alternately impressing current from said sources on said lamp thereby varying invisibly its light emission 25 in a predetermined order, and a receiver for detecting said variations, said receiver consisting of a rotating disk with apertures therein whereby said light may be viewed intermittently.

30 11. In a secret signaling system, an electric lamp, a source of direct current for said lamp, a source of alternating current for said lamp, means for alternately impressing current from said sources on said lamp 35 thereby varying invisibly its light emission in a predetermined order, a receiver for detecting said variations, said receiver consisting of a disk with perforations therein, and means for causing said perforations to follow each other with a frequency of the order 40 of twice the frequency of said alternating current source.

12. The combination of a translating device, a plurality of means for supplying current thereto, and means for shifting from one of said means to the other while maintaining substantially constant the effective value of the current supplied to said device during the shifting.

13. The combination of an electric lamp, 50 means for supplying alternating current and direct current thereto, and means for gradually shifting the current supply from one to the other of said currents.

14. The combination of an electric lamp, 55 means for supplying alternating current and direct current thereto, and means for shifting the current supply from one of said currents to the other while maintaining substantially constant the intensity of the 60 illumination of the light from the lamp.

15. The method which comprises supplying current from a source to a translating device and substituting for said source a second source while supplying effectively 65 the same amount of current to said device during the substitution of one of said sources for the other of said sources.

16. The method which comprises supplying current to a device at times from one 70 source, supplying current to said device at times from another source and gradually shifting from one of said sources to the other of said sources without disconnecting said device from said sources and while 75 maintaining substantially constant the amount of current supplied to said device during said shifting.

17. The method which comprises supplying current to a translating device substantially entirely at times from one source, supplying at other times current to said device substantially entirely from a second source and shifting from one of said sources to the other of said sources while supplying 80 effectively the same amount of current to said device by gradually decreasing the amount of current supplied by one of said sources and by gradually increasing the amount of current supplied by the other of 85 said sources until the current supplied to said device is derived substantially from one of said sources alone.

In witness whereof, I hereunto subscribe my name this 29th day of December, A. D. 95 1916.

HAROLD D. ARNOLD.
